UNITED STATES PATENT OFFICE.

MAX E. GORMAN, OF NEWARK, NEW JERSEY.

TOOL HOLDER.

Application filed July 27, 1923. Serial No. 654,198.

This invention relates to tool holders and has for its primary object the provision of a holder for interchangeably receiving tools of different types.

5 Another object of the invention is to provide a holder capable of locking a tool therewith and wherein the use of a drift bar, wedge or other like implement is dispensed with for removing the tool from the holder.

10 A further object of the invention is the provision of a quick and efficient means of securing or removing a tool from its holder.

15 A still further object of the invention is to provide a novel form of holder which is simple in construction, cheap of manufacture and easy of operation.

20 With these and other objects in view, the invention resides in the certain novel construction and combination and arrangement of parts, the essential features of which are hereinafter fully described, are particularly pointed out in the appended claim, and are illustrated in the accompanying drawing, in which:

25 Figure 1 is a vertical section view through my improved holder showing a tool secured thereto.

Figure 2 is a horizontal sectional view on the line 2—2 of Figure 1.

30 Figure 3 is a perspective view of the holder and tool separated.

Figure 4 is a detail perspective view of the clamping jaws.

35 Hitherto, holders of this class have been provided with a tapering bore for the reception of a tapering shank formed on a tool, the same being wedged together for frictional contact. These holders are usually provided with a slot communicating with the bore and in which is adapted to be inserted a drift bar, wedge, or other like implement for contact with the shank for ejecting the tool therefrom. This is objectionable as it required the use of an additional 40 implement which must be always handy for the removal of the tool and which implement may be misplaced, thereby causing a loss of time to the workman until the same 45 may be found. It is therefore my invention to eliminate this extra implement and the same is clearly set forth in the following.

45 Referring more particularly to the drawing, the reference numeral 10 designates a holder or stock of any suitable size and material but the same is preferably constructed 50 of steel, the holder further serving as a

handle when the same is in use. The holder 10 is formed with a vertical bore 11 whose diameter is the same throughout its length, one end of the bore opening at the bottom 60 of the holder and the other end opening into a slot 12 formed slightly below the center of the holder. A pair of semi-circular clamping jaws 13 are pivotally mounted as at 14 to the side walls of the slot and the 65 same are adapted to co-act with the shank of the tool presently to be described. A spring 15 serves to constantly hold the jaws in a closed position. The jaws 13 are each formed with a manipulating portion 15 70 whereby the same are adapted to be separated by compression of these portions by the fingers of the hand.

The numeral 16 designates a tool of any 75 suitable type such as a chisel, screw driver or wrench, but in the present instance I have shown the same as constituting a rivet tool. The tool 16 includes a head 17 provided with a shank 18 of a diameter to snugly fit in the bore 11 of the holder. The extreme end of the shank 18 is provided with a ball-shaped head 19 for co-action by the jaws 13 when the shank has reached the limit of its insertion. In order to prevent rotation of the tool with relation to the holder, I form 80 the holder 10 at the bottom thereof, with a pair of slots or kerfs 20 for receiving the lugs 21 extending upward from the head 17 of the tool. The head 17 of the tool 16 is provided with a semi-circular recess 22 85 adapted to receive the stud end of the rivet whereby a succession of blows imparted to the end of the handle will cause a head to form on the rivet and a size equal to the size 90 of the recess. It is of course understood that a set of these tools having various size recesses may be used in connection with a single holder and also certain other tools hereinbefore mentioned.

95 In operation the shank 18 of the tool is 100 inserted in the bore 11 of the holder until the head 19 contacts with the open mouth portion 23 of the jaws 13, thereby separating the same against the tension of the 105 spring. When the shank has reached the limit of its insertion, the jaws 13 will close about the head, and the lugs 21 will have entered their respective slots so as to hold the tool in its proper position within the 110 holder. To remove the tool from the holder, the manipulating portions are depressed to disengage the jaws from the head and the

tool withdrawn. It will be noted that a blow imparted to the end of the holder will not cause undue strain upon the jaws as the force is taken up by the contact of the shoulders of the head with the end of the holder.

While I have described what I deem to be the most desirable embodiment of my invention, it is obvious that many of the details may be varied without in any way departing from the spirit of my invention, and I therefore do not limit myself to the exact details of construction herein set forth nor to anything less than the whole of my invention limited only by the appended claim.

15. What is claimed as new is:

In a device of the class described, the combination of a holder having a straight bore therein, a recess formed in said holder and communicating with one end of said bore, a pair of movable co-acting cup shaped jaws

mounted within said recess, spring means for normally holding said jaws in closed position, a restricted mouth formed by said cup-shaped jaws, a tool having a shank for insertion in said bore, a spherical head on the 25 free end of said shank for co-action with the walls of the restricted mouth upon insertion of said shank in said bore for automatically expanding said jaws against the spring means for permitting said head to be seated within and enclosed by the jaws upon the limit of insertion of said tool in said holder, and manipulative portions extending from said jaws and operable for manually expanding said jaws from about said head to permit said tool to be removed from said holder.

30 In testimony whereof I have affixed my signature.

MAX E. GORMAN.
